UNITED STATES PATENT OFFICE

2,326,289

SPAR

William J. De Shong, Union Springs, N. Y.

Application December 3, 1941, Serial No. 421,506

1 Claim. (Cl. 114—90)

The present invention relates to new and useful improvements in spars, and has for its primary object to provide, in a manner as hereinafter set forth, a device of this character which is particularly adapted for use on power boats whereby a balloon jib may be conveniently used on boats of this type, thus saving fuel and engine wear in addition to providing an auxiliary source of power in emergencies, such as engine failure.

Another very important object of the invention is to provide a spar of the aforementioned character which may be expeditiously erected and taken down, and which, when not in use, may be placed in an out-of-the-way position on the deck of the boat.

Other objects of the invention are to provide a spar of the character described which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view, showing a spar constructed in accordance with the present invention erected on a boat.

Figure 2 is a view in side elevation thereof.

Figure 3 is a cross-sectional view through the boat, taken substantially on the line 3—3 of Figure 2, showing the spar in rear elevation.

Figure 4 is a vertical sectional view through the upper portion of the device, taken substantially on the line 4—4 of Figure 2.

Referring now to the drawings in detail, it will be seen that the embodiment of the invention which has been illustrated comprises an inverted substantially U-shaped frame of suitable wood or other material, which is designated generally by the reference numeral 1. Sockets 2 are provided on the deck 3 of a power boat 4 adjacent the forward end of the cabin 5 of said boat. The sockets 2 are for the reception of the end portions of the frame 1.

The frame 1 includes a pair of substantially duplicate, complementary, oppositely curved or bowed sections 6 to which forwardly and rearwardly extending stays 7 are connected at 8. One end of the sections 6 are detachably connected

in opposed relation through the medium of a bolt 9 (see Fig. 4). Mounted on these end portions of the sections 6 are metallic channel members 10. Rigidly secured by screws 11 on the opposed ends of the sections 6 and depending therefrom are hangers 12 in the form of metallic straps. A pulley 13 is suspended from the hangers 12. The bolt 9 passes through openings which are provided therefor in the channel members 10 and the hangers 12. Brace elements 13' are provided between the spar sections 6 and the hangers 12. The other ends of the sections 6 are engageable in the sockets 2.

A peak halyard 14 is trained over the pulley 13 and connected to the upper portion of a balloon jib 15. The lower corner portions of the jib 15 are secured by sheet ropes 16 to cleats 17 on the boat 4.

It will thus be seen that a spar has been provided which may be expeditiously erected on power boats and taken down when desired. When the spar is not in use, the sections 6 are separated by simply removing the bolt 9 and the pulley 13. The sections 6 are then lashed to the sheers 18 of the boat 4 to the curvature of which said sections substantially conform, as suggested in dotted lines in Figure 1 of the drawings. Of course, the stays 7 are disconnected when the spar is to be taken down.

It is believed that the many advantages of a spar construction in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

40. What is claimed is:

A spar including a substantially U-shaped frame, said frame comprising a pair of oppositely bowed, complementary half sections connected at one end, channel members mounted on the adjacent end portions of the sections, a pair of opposed, abutting hangers mounted on the connected ends of the sections and depending therefrom, a bolt extending through the channel members, the adjacent end portions of the sections and the hangers for securing said sections together, and a pulley suspended from the hangers.

WILLIAM J. DE SHONG.
